UNITED STATES PATENT OFFICE.

HORACE D. STEVENS, OF AKRON, OHIO, ASSIGNOR TO THE FIRESTONE TIRE AND RUBBER COMPANY, OF AKRON, OHIO, A CORPORATION OF OHIO.

TUBE-CUFFING DEVICE FOR STRIPPING MACHINES.

Application filed July 17, 1925. Serial No. 44,380.

This invention relates to devices for cuffing the ends of vulcanized inner tubes while on their mandrels over the end or muzzle of a tube-stripping gun in preparation for the 5 stripping action.

In the co-pending application of Horace D. Stevens and Edward D. Putt, Serial No. 3,002, filed January 17, 1925, there is disclosed a mechanism for stripping inner tubes 10 consisting of an air cylinder or gun for receiving the mandrels having the tubes thereon and arranged to be supplied with air under pressure so that when an end of the tube is cuffed back onto the gun and the mandrel is 15 withdrawn, the air will maintain the reversely turned portion of the tube expanded away from the portion of the tube on the mandrel to prevent friction of the turned portion on that portion on the mandrel which 20 would be so great as to prevent the stripping operation being carried out.

It has been found that the cuffing of the tube on the muzzle of the gun which has heretofore been accomplished by hand is an exceedingly fatiguing operation on the fingers, the stretching of the tube requiring the expenditure of great strength and causing a sort of paralytic condition in the hand and bleeding about the finger nails after the cuffing operations have been repeated a number of times.

The general object of the present invention is to provide a device for cuffing the tube onto the muzzle of the gun.

35 A particular object is to provide a device carrying a series of contractile and expandible fingers, arranged to have the tube easily cuffed thereon when contracted and adapted to expand the cuff onto the muzzle of the gun.

40 A further object is to provide a device of the type described above which will be movable on the gun and will be operable by the muzzle of the gun due to such movement.

45 The foregoing and other objects are obtained by the construction illustrated in the accompanying drawings and described below. It is to be understood that the invention is not limited to the specific form thereof shown and described.

50 Of the accompanying drawings:

Figure 1 is a side elevation of a device embodying the invention mounted on a gun and shown in position for a cuffing operation;

55 Figure 2 is a similar view showing the first step of the cuffing operation;

Figure 3 is a similar view illustrating the manner in which the fingers are spread to expand the cuff onto the muzzle of the gun;

Figure 4 is a similar view illustrating the completed operation; and

Figure 5 is an end elevation of the device as shown in Figure 1.

Referring to the drawings, 10 is the muzzle end of a stripping gun, containing a mandrel 11 projecting therefrom, the mandrel 11 having a tube 12 thereon which is to be stripped therefrom.

The cuffing device of the invention includes a sleeve 13 slidable on gun 10 adjacent the muzzle thereof and having pivoted thereon a circumferential series (in this case four) of fingers 14, 14 each formed with spaced prongs 15, 15 adapted to engage the outer surface of tube 12 in the manner shown in Figure 1. Fingers 14, 14 are normally urged or contracted inwardly by means of tensile springs 16, 16 connected between pins 17, 17 mounted on the fingers 14.

In the operation of the device the sleeve 13 is moved toward the muzzle end of gun 10 until fingers 14 lie on tube 12 substantially as shown in Figure 1. The tube is then easily stripped or rolled back onto the free ends of the fingers 14 as shown in Figure 2.

Sleeve 13 is now moved away from the muzzle of gun 10 and the inner surfaces of fingers 14 engage the muzzle of the gun and are spread thereby against the action of springs 16 to expand and carry the reversely turned end of the tube onto the muzzle 10 in the manner illustrated in Figure 3. Movement of the sleeve 13 away from the muzzle is continued until the entire projecting portion of the tube 12 on the mandrel 11 has been cuffed back onto the gun and the fingers 14 withdrawn from beneath the cuff as is illustrated in Figure 4.

It will appear from the foregoing that the manual part of the cuffing operation has been reduced to an easily and quickly accomplished step and that the device is adapted to perform the difficult stretching operation which has been objectionable in the use of mechanical stripping devices in the past.

Modifications of the invention may be resorted to without departing from the spirit thereof or the scope of the appended claims.

What I claim is:

1. Apparatus of the class described, comprising the combination with a cylinder for

receiving a mandrel, of a device for cuffing the end of a tube on said mandrel onto the end of said cylinder; said device including a series of pivoted fingers, a mounting for the fingers slideable on the cylinder, and yielding means normally tending to contract the fingers whereby movement of the mounting on the cylinder will effect a spreading of the fingers against the action of said yielding means by engagement of the fingers with the end of the cylinder.

2. Apparatus of the class described, comprising a cylinder for receiving an inner tube mandrel, a mounting movable on the cylinder, and a circumferential series of yieldable fingers carried by the mounting and normally tending to contract to a diameter less than that of the cylinder but adapted to be expanded to the diameter of the cylinder by engagement therewith.

3. Apparatus of the class described, comprising a cylinder for receiving an inner tube mandrel, and a device movable along the cylinder including a series of fingers tending

normally to contract onto a tube on the mandrel but adapted to be spread by engagement with the cylinder to expand the cuff of an inner tube thereon.

4. Apparatus of the class described, comprising a hollow cylinder of comparatively large diameter adapted to receive a mandrel, and means for cuffing a tube on the mandrel onto the cylinder, said means comprising a movable mounting and a circumferential series of yielding fingers on the mounting arranged about the cylinder.

5. Apparatus of the class described, comprising the combination with a hollow cylinder of means movable thereon for cuffing over the end of the cylinder a tube arranged within and projecting from the cylinder on the cylinder.

6. A device of the class described, comprising a sleeve; a circumferential series of contractible and expansible fingers on said sleeve, and means normally yieldingly contracting the fingers.

HORACE D. STEVENS.
